UNITED STATES PATENT OFFICE

STANLEY M. KENERSON, OF SPRINGFIELD, MASSACHUSETTS, ASSIGNOR TO STANDARD ELECTRIC TIME COMPANY, OF SPRINGFIELD, MASSACHUSETTS, A CORPORATION OF CONNECTICUT

ELECTRIC PLUG

Application filed September 18, 1928. Serial No. 305,809.

Objects of the present invention are to provide an electric plug of the type adapted to fit into a wall receptacle or other jack which is simple and economical in construction, which is durable and reliable in use and which is generally superior to plugs of this type as heretofore constructed.

The features of the invention will be evident from the following description and 10 claims and the illustration of one concrete embodiment in the accompanying drawings, in which

Fig. 1 is a side view of the plug;

Fig. 2 is a transverse central section on line 15 2—2 of Fig. 1;

Fig. 3 is a longitudinal central section;

Fig. 4 is a bottom plan view with parts removed;

Fig. 5 is a sectional view similar to Fig. 2, 20 illustrating an optional construction;

Fig. 6 is an end elevation of a modification;

Fig. 7 is a section on line 7—7 of Fig. 6;

Fig. 8 is a central longitudinal section 25 taken at right angles to the section of Fig. 7, showing the plug inserted in a jack;

Fig. 9 is a front elevation of a modification;

Fig. 10 is a central longitudinal section of 30 a further modification adapted for two cables; and

Fig. 11 is a front elevation of the modification shown in Fig. 10.

The particular embodiment of the invention shown in Figs. 1 to 4 comprises top and 35 bottom parts 1 and 2 of suitable insulating material, screws 3 for holding these parts together, five contact terminals 4, 5, 6, 7 and 8 fastened to the bottom part 2 by means of tubular rivets 9, an elongate metallic bar 10 secured to the bottom part by means of a 40 screw 11, and two spring detents 12 and 13 fastened to the bottom part by means of rivets 14.

As shown in Figs. 2 and 3, the upper surface of the bottom part 2 is recessed to 45 accommodate the conductors which are connected to the contact terminals 4 to 8 inclusive within the tubular rivets 9. As shown in Fig. 2 the contact terminals 4 to 8 inclusive 50 are L-shaped and one end of each terminal is

hooked over a flange 15, as shown at 16, the end of the terminal extending into a groove extending longitudinally of the lower face of the part 2, two such grooves 17 and 18 being provided for the two series of terminals 4, 5, 6 and 7, 8. By hooking the terminals as aforesaid, each terminal may be held firmly in position by means of a single rivet 9.

The fasteners 12 and 13 are formed of 60 spring material and fit in notches 24 in the ends of bar 10 and each is provided with a shoulder 19 for engagement behind the plate 20 of the wall receptacle. The part 2 is recessed along its lower edges to accommodate the face plate 21 of the wall receptacle, it being understood that the parts 20 and 21 form 65 no part of the plug but merely cooperate therewith to hold the plug in operative position with the terminals 4 to 8 inclusive engaging the terminals of the jack mounted in 70 the wall receptacle.

In order to prevent the plug from being inserted in the jack in reversed position, a lug 22 is mounted on the plug to extend into a recess 23 of the wall receptacle when the plug is inserted in the proper position, the lug 22 obstructing the insertion of the plug in the reverse position. The plate 21 may be secured over the plate 20 in any suitable way as by spring clips, one of which is shown 80 at 25 in Fig. 2. In the optional arrangement shown in Fig. 5, a forward projection of the plate 20 is received within a supplemental recess on one side of the bar 10, to insure proper insertion of the plug 10.

Figs. 2 and 3 illustrate one form of means 85 for clamping the covering of the cable 40 between the body 2 and cover 1 of the plug to relieve strain on the cable wires resulting from pulls on the cable 40. This means comprises a plate 50 fixedly or detachably mounted in a recess in the cover 1 and having an opening somewhat smaller than the opening in the cover 1 so as to indent the periphery of the cable covering when the cable is pulled 90 through the cover. Thus when the cover 1 is forced against the back of the body 2 by means of screws 3 the projecting portion of the cable covering is squeezed between the plate 50 and the back of body 2, causing it to 95 100

bulge out and be clamped in position as illustrated in Figs. 2 and 3.

The modification shown in Figs. 6 to 9 inclusive is similar to the embodiment shown in Figs. 1 to 5, corresponding parts being correspondingly designated. However, this modification differs in the following respects: The metallic piece 10 is omitted and instead of the lug 22 fitting into recess 23 the forward projection 30 of the body 2' is provided with a recess 31 adapted to receive the lip 32 on the front plate 20' of the receptacle containing the jack 34 (Fig. 8) into which the plug is to be inserted, thereby to prevent the plug being inserted into the jack in reverse position.

Instead of the spring fasteners 12 and 13, the modification shown in Figs. 6 to 9 inclusive is provided with circular lugs 33 having rounded ends adapted to engage spring contact fingers 35 of the jack frictionally to hold the plug in position with the contact pieces 4' to 8' engaging the contact pieces 36 of the jack respectively, this jack being described and claimed in a copending application filed 25 on even date herewith. The lugs 33 are mounted in recesses 37 in the forward face of the body 2' of the plug at each end of the central projection 30 by means of screws 3' extending through the cover 1' and thence 30 threading into the lugs. Thus the screws 3' serve the double function of holding the cover 1' on the body 2' and also holding the lugs 33 in place.

The means for gripping the covering of the cable 40, to relieve the strain on the wires when the cable is pulled, is somewhat different from that shown in the preceding figures. A conical member 41 is mounted on the rear face of the body 2' in alignment with the cable opening of the cover to force the cable covering 42 outwardly against the peripheral edge 43 of the cable opening and thereby clamp the cable covering between this conical piece and the cover when the cover is forced 45 against the body 2' by means of screws 3'. The conical part 41 may be formed integrally with the body 2' or it may be in the form of a separate piece of insulation bearing on the back of the body 2' or preferably seating in a 50 recess 44 as shown in the figures. In assembling the parts the cable is first inserted through the cover 1', the wires are then spread outwardly from the axis of the cable so as to be distributed around the conical 55 projection 41, the ends of the wires are then connected to the contact pieces 4' to 8' inclusive by means of the connectors 45, and the cover 1' is then forced into place against the back of the body 2', whereupon the cable cov- 60 ering is clamped as aforesaid to relieve the strain on the wires 46 resulting from pulls on the cable 40 to which plug cables are ordinarily subjected.

The modification shown in Figs. 10 and 11 differs from that shown in Figs. 6 to 9 inclu-

sive only in that the plug is constructed for attachment to two cables leading from the same contact pieces, as for example in the case of two bed switches in a hospital ward being connected to the same plug. In this modification the lugs 33 are held in place by screws 47 other than the screw 48 which holds the cover 1' on the body 2'. The cover 1' is provided with two cable openings and two conical pieces 41' in alignment with the openings respectively for spreading the cable coverings as above described.

I claim:

1. An electric plug comprising a body of insulation having a central projection on its forward face, a plurality of contact pieces mounted on the body on opposite sides of the projection, the forward ends of the ends of the contact pieces being hooked over the projection, a bar secured to the face of the projection over said hooked ends, said bar having notches in its opposite ends, and holding lugs received in said notches and fastened to the body at opposite ends of the projection for frictionally retaining the plug in a jack, the lugs being insulated from the contact pieces and projecting forwardly beyond the projection and the contact pieces.

2. An electric plug comprising a body of insulation having a central projection on its forward face, a cover on the rear side of the body, a plurality of contact pieces mounted on the body on opposite sides of the projection; the forward ends of the ends of the contact pieces being hooked over the projection, holding lugs fastened to the body at opposite ends of the projection for frictionally retaining the plug in a jack, the lugs being insulated from the contact pieces and projecting forwardly beyond the projection and the contact pieces, and fasteners extending through the cover and body into the base of the lugs for securing both the cover and the lugs to the body.

Signed by me at Boston, Massachusetts this 110 fifth day of September, 1928.

STANLEY M. KENERSON.
